COMBINED STEP STOOL AND ADJUSTABLE SEAT UNIT

Robert J. Dottinger, Hawthorne, N.J., assignor to Cole Steel Equipment Co., Inc., New York, N.Y., a corporation of Delaware

Filed Feb. 23, 1968, Ser. No. 10,688

Term of patent 14 years

Int. Cl. D6—01

U.S. Cl. D15—8

FIG. 1

Des. 216,508

PAGE 2

FIG. 2

FIG. 3

FIG. 1 is a perspective view of a combined step stool and adjustable seat unit embodying my new design with the adjustable seat in a partially raised position;

FIG. 2 is an elevational view of the combined step stool and adjustable seat unit of FIG. 1 with the adjustable seat in its housed position; and

FIG. 3 is a top view of the combined step stool and adjustable seat unit of FIG. 1 with the seat unit disposed in position over the top step thereof.

I claim:

The ornamental design for a combined step stool and adjustable seat unit, as shown and described.
